DANIEL W. TOWER, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

LATCH AND LOCK.

1,172,323.

Specification of Letters Patent.

Patented Feb. 22, 1916.

Application filed May 25, 1914. Serial No. 840,817.

To all whom it may concern:

Be it known that I, DANIEL W. TOWER, a citizen of the United States of America, residing at Grand Rapids, in the county of Kent and State of Michigan, have invented 5 certain new and useful Improvements in Latches and Locks; and I do hereby declare the following to be a full, clear, and exact description of the invention, such as will 10 enable others skilled in the art to which it appertains to make and use the same.

This invention relates to locking devices for use in connection with latches for closing swinging doors and holding the same 15 in closed position, the lock being adapted to firmly retain the latch in closed position such that it cannot be moved to release the door except after the lock has been released for such purpose.

20 It is an object of this invention to provide a very simple and compact lock, one that can be easily and cheaply manufactured and assembled, and to provide such lock with various new and useful features hereinafter 25 more fully described and particularly pointed out in the claims, reference being had to the accompanying drawings in which:

Figure 1 is a front elevation of a part of a door and casing with my improved construction applied thereto; Fig. 2 is an inverted plan view of the same, the door and casing therefor and portions of the latch being shown in section; Fig. 3 is a view of the lock detached from the casing and looking 35 into the inner side thereof, certain parts being removed to disclose the construction; Fig. 4 is a central vertical section through the lock portion of the device; Fig. 5 is a side elevation of a detail of the locking 40 mechanism; Fig. 6 is a plan view of the sliding locking plate used in the device and indicating the manner of operation thereof by the key; and Fig. 7 is a perspective view of the friction device for frictionally holding 45 the locking plate in the position to which it is operated.

Similar reference characters refer to similar parts throughout the several views of the drawing.

50 The lock and latch as shown in the drawing are applied to swinging door constructions, a part of the casing at 1 and of the door at 2 being shown to which members lock and latch are secured, there being a handle 55 member 3 having an integral extension 4

secured by means of screws or other equivalent fastening means to the door. The extension 4 is thicker where it joins on to the handle at 5 than it is at its end, there being formed a cam surface 60 with a substantially uniformly increasing inclination from the end of the cam to the handle as indicated in dotted lines, Fig. 2, said cam surface forming a bearing surface against which the adjustable 65 plate 7 secured to a movable part of the latch as hereinafter described bears when such movable part is carried in proximity to the handle, the plate 7 being adjusted toward the cam surface by means of 70 the screw 6, while plate 7 may be of spring material having a tendency to move toward the movable latch part to which it is secured. Projecting substantially at right angles 75 from the member comprised of handle 3 and cam 4 at a point adjacent the junction of the handle and cam is an integral arm 8, the side of which toward the handle 3 is undercut forming an inclined surface the use of 80 which will later appear.

The movable latch member to which the plate 7 is secured as described is comprised of a head 9 at one end from the side of which projects the integral cam 10, while at substantially right angles to cam 10 projects a handle 11 by means of which said member may be manually moved. The head 9 is practically cylindrical in form with its outer end closed except for a central circular opening adapted to receive one end of 85 a rotative key pin in the axis in one head as shown, and having a slot in one side thereof for the reception of a flat key used in locking and unlocking the latch, the head 9 also being slotted so that when the slots 90 in the pin and head are brought into conjunction a flat key may be inserted. The cylindrical head is mounted for pivotal movement in a housing 21 which is secured 95 firmly by any suitable fastening means to the door casing 1. At its inner end the head 9 has secured thereto a disk 14 having portions as at 15 fitting into slots in the head 9 whereby said disk is fixed on the head. This disk has a recess in its outer edge as shown in Fig. 3 thereby forming two shoulders spaced apart and adapted to impinge against the stop 16 projecting inwardly from a side of the housing 21, whereby 100 the pivotal movement of the head 9 is 105 110

limited, and that handle 11 can be moved only through a limited arc, preferably of about ninety degrees or between the positions indicated by the broken and full line positions thereof, as shown in Fig. 1.

Fixed in the bottom of the housing 21 is a backing plate 17 formed from resilient material and having struck from the sides thereof the spring members 18 which bear 10 against a locking plate 19 located between the disk 14 and the plate 17. The locking plate 19 has a projection 20 at one edge thereof which extends at right angles from the plate into the plane of the disk 14 and in 15 one position of said plate 19 the projection 20 may be moved into the recess in the margin of the disk 14 as indicated in Fig. 3. The locking plate 19 is held spaced apart from the disk 14 by the shoulders 22 integral 20 with the casing 21 and centrally the locking plate is provided with an opening 23 substantially rectangular in shape through which the pin 12 passes, the inner end of the pin being journaled in an opening in the 25 plate 17. The distance between the parallel sides of the opening 23 nearest each other is substantially equal to the thickness of the pin 12 plus the depth of the recess in the disk 14, so that the sliding movement of the 30 locking plate 19 will move the projection 20 into and out of the recess as the key is turned.

In assembling the device, the head 9 is inserted into the housing 21 and the disk 14 35 secured to the head to turn therewith. The locking plate 19 is then placed against the shoulders 22 with the projection 20 in proper relation to disk 14 and the slotted pin 12 passed through the opening 23, its 40 end seating in the opening in the head 9. Finally the spring backing plate 17 is placed to practically close the casing, its spring members 18 bearing against the locking plate 19 and the other end of the pin 12 45 rotative in the central opening thereof said opening being shown in Fig. 7. The whole is now positioned at the proper place on the door casing 1 and attached thereto, the screws passing through the outer openings 50 in plate 17 and holding it in place. With the locking plate located so that its projection 20 is outside the peripheral limits of the disk 14, the handle 11 may be moved back and forth at will through the degree 55 limit set by the stop 16, it being evident that when the handle 11 is moved to the full line position of Fig. 1, it will ride on the inclined cam surface of extension 4 closing the door tightly and that as it is brought 60 to its other extreme of movement, the cam 10 will engage under and against the inclined side of the arm 8, causing the door 2 to be swung partially open so that it can be easily opened by grasping the handle 3. 65 The cam 10 is of utility, particularly when

the door 2 sticks and is hard to open by a direct pull on the handle 3 as may often be the case, especially with refrigerator doors. When the door is thus latched, as shown in Fig. 1, it will be seen that the slot in pin 12 70 may be brought into conjunction with the slot in the head 9 so that the wider key with its projection 24 at its end may be inserted, such key having its end reaching to the locking plate 19 and into the opening 23 75 thereof, whereby on turning the key the projection 24 will engage against the side of the opening 23 adjacent to the pin 12, thereby giving to said plate a sliding movement. When the handle is in latching position, as shown in Fig. 1, the disk 14 will be located with reference to projection 20 of locking plate 19, as shown in Fig. 3, and on then turning the key the plate may be moved so that the projection will enter the 80 recess of the disk 14, with the projection 20 positioned to stop the rotation of the disk in one direction and the stop stopping the rotation in the same in the opposite direction; the head 9 and attached handle 11 85 are thus firmly held in position and cannot be moved until such time as the locking plate is oppositely moved by the key to move the projection 20 outside the peripheral limits of the disk 14. The plate 17 90 with its spring members 18 bearing against the locking plate 19 retains said plate 19 against accidental displacement after it has once been moved to either of its positions, such frictional retention, however, being 95 easily overcome on manual operation of the key to move the plate 19 either to the locking or unlocking positions.

From the foregoing description it will be seen that I have provided a very efficient 105 and durable lock for latches, one very simple in construction and operation and having no parts liable to get out of order.

Various changes in minor detail may be made without departing from the invention which is defined in the appended claims, 110 all modifications coming within their scope being comprehended in my invention.

Having thus fully described my invention, what I claim as new and desire to secure by Letters Patent, is:—

1. In a device of the character described, a housing adapted to be attached to a door casing, a handle having an integral head rotative in the housing, means for limiting the rotative movement of the head and handle, a lock located within the housing for holding the handle at one extreme of its pivotal movement, and means adapted to receive a key for operating the lock located in 120 the axis of the head.

2. In a device of the character described, a housing adapted to be attached to a door casing, a handle member having a substantially cylindrical head at one end thereof 130

5 rotative in the housing, a disk fixed to the head and within the housing, said disk having a recess in the periphery thereof, a slide-
6 able plate, a projection on the plate to enter the recess and lock the head, and means for
7 sliding the plate arranged in the head.

8 3. In a device of the character described,
9 a housing adapted to be attached to a door
10 casing, a handle member having a substan-
11 tially cylindrical head at one end thereof,
12 said head being rotative in the housing, a
13 disk fixed on the head and having a peripher-
14 al recess, a stop extending from the hous-
15 ing into the recess, a locking plate slidably
16 mounted adjacent the disk and having a
17 projection to enter the said recess, and
18 means for shifting said locking plate to
19 move the projection into and out of the re-
20 cess, said means being located in the cylin-
21 drical head.

22 4. In a device of the character described,
23 a housing adapted to be attached to a door
24 casing, a handle member having a substan-
25 tially cylindrical head at one end thereof,
26 said head rotatably mounted in the housing,
27 a disk fixed on the head and within the hous-
28 ing, said disk having a peripheral recess, a
29 stop extending from the housing into the
30 said recess, a locking plate slidably mounted
31 opposite the disk and having a projection
32 extending therefrom toward the disk, said
33 projection being moved beyond the periph-

34 ery of the disk or within the said recess by
35 movement of the locking plate, a plate posi-
36 tioned adjacent the locking plate and hav-
37 ing spring members bearing against the
38 locking plate to frictionally retain it in po-
39 sition, a pin having its ends mounted rota-
40 bly in said plate and handle and having
41 a slot to receive a key to project laterally
42 therefrom to engage and move the locking
43 plate.

44 5. In a device of the character described,
45 a door, a casing therefor, a lever pivotally
46 mounted on the casing and having a limited
47 movement whereby the handle may be posi-
48 tioned opposite the door or clear of the same,
49 a cam attached to the door having increas-
50 ing thickness in the direction of movement
51 of the lever when moved opposite the door,
52 said lever also engaging the cam to tightly
53 close the door, a plate attached to the han-
54 dle member on the inner side thereof and
55 adapted to bear immediately against the
56 cam, and means for adjusting the said plate
57 toward the cam member, substantially as
58 described.

59 In testimony whereof I affix my signa-
60 ture in presence of two witnesses.
